Patented Nov. 11, 1919.

INVENTOR

UNITED STATES PATENT OFFICE.

EDWARD D. MACKINTOSH, OF BROOKLYN, NEW YORK, ASSIGNOR TO S. S. HEPWORTH COMPANY, OF NEW YORK, N. Y., A CORPORATION OF NEW YORK, AND EDITH M. MACKINTOSH, OF BROOKLYN, NEW YORK.

CENTRIFUGAL MACHINE.

1,321,766.

Specification of Letters Patent.

Patented Nov. 11, 1919.

Application filed October 30, 1918. Serial No. 260,266.

To all whom it may concern:

Be it known that I, EDWARD D. MACKINTOSH, a citizen of the United States, residing at Brooklyn, in the county of Kings and the State of New York, have invented a new and useful Improvement in Centrifugal Machines, of which the following is a specification.

The object of my invention is the automatic discharge, from the basket of a centrifugal machine, of the material treated therein.

Referring to the accompanying drawings, forming part of this specification:

Figure 1 is a vertical section of the basket of a centrifugal machine embodying my improvement.

Figs. 2 and 3 are detached views of details.

The top *a* and the cylindrical wall *b*, of the basket, are of a very common construction but the bottom consists of the frustum of a hollow cone *c* secured to a flange *d*. This flange has a sleeve *e* sliding axially on a hub *f* carried by the usual spindle *g*. A feather *h*, let into the hub, extends into a spline *i* in the sleeve and prevents it from turning on the hub.

On the bottom of the hub is a head *j* connected to and supporting the basket wall by means of a series of yokes *k* and a ring *l*.

Ears *m* and *n*, forming parts of the flange *d* and the head *j*, are connected by means of a series of toggles pivoted to them, these toggles consisting of levers *o* and *p* pivoted together at *q*.

Springs *r* tend to open the toggles and lift the basket bottom. They are meant to be of just about sufficient strength to lift it to its highest position but, when the basket is rotating, its bottom is also held up in its highest position by the action of centrifugal force on the toggles. This tends very strongly, at the high speed employed in the

operation of a centrifugal machine, to force them outwardly, away from the center of the basket.

A cloth frustum of a cone, *s*, secured to the flange and the head, forms a chamber inclosing the toggles and prevents them from agitating the surrounding air.

To the top of the hub *f* is secured a disk *t*, and an annular disk *u* is secured to the lower part of the basket and projects over the gutter *v* commonly forming part of a centrifugal machine.

In operation the material to be treated is dropped on the disk *t* while it is rotating at a high speed. The disk throws it against the wall *b* on which it collects to a considerable thickness that is quite uniform. When the treatment of the material is finished the basket is stopped and the treated material, resting on the conical part *c*, of the bottom, forces it down and drops out. The basket is then rotated again, the toggles force the basket bottom up to its highest position, and the entire operation is repeated again and again.

I claim:

1. A centrifugal basket having an axially movable bottom, a head below the bottom, fixed to the spindle of the centrifugal, and carrying the wall of the basket, and a series of toggles connecting the head and the bottom, extending inwardly therefrom toward the center of the basket, and supporting the bottom.

2. A centrifugal basket having an axially movable bottom, a head below the bottom, fixed to the spindle of the centrifugal and carrying the wall of the basket, a series of toggles connecting the head and the bottom, extending inwardly therefrom toward the center of the basket, and supporting the bottom, and springs tending to open the toggles and lift the bottom.

EDWARD D. MACKINTOSH.
